UNITED STATES PATENT OFFICE.

THOMAS DENTON MILLER, OF CLARKSVILLE, MARYLAND.

SHINGLE.

Application filed November 6, 1925. Serial No. 67,408.

This invention relates to shingles having several plane portions offset by transverse relatively abrupt ramps, the ramps facilitating the laying of the shingles and serving as a means for preventing water from passing through the roof, and also having a certain desired architectural effect when assembled on a roof. In the present invention, the shingles each have two transverse ramps and the distance between the lower edge of the shingles and the lowermost ramp is substantially the same as the distance between the ramps, so that when the shingles are assembled upon a roof the lower edges of the shingles of one row will coincide with the upper edges of ramps in the shingles of the lower row. Thus, at the ends of the shingles in each row, the appearance of double thickness is given, which is desirable architecturally.

In the accompanying drawing,

Fig. 1 is a plan view of a shingle made in accordance with my invention, the shingle in this view having rectangular and triangular portions offset from one another by a ramp;

Fig. 2 is a plan view of a part of a roof covering composed of shingles like that shown in Fig. 1;

Fig. 3 is a section on the line 3—3 of Fig. 2;

Fig. 4 is a plan view of a modified form of shingle, having triangular and rectangular portions, and having a ramp slightly below the base of the former portion, the rectangular portion being narrowed below this ramp;

Fig. 5 is a section on the line 5—5 of Fig. 4;

Fig. 6 is a plan view of an assemblage of shingles of the form shown in Fig. 5;

Fig. 7 is a section on the line 7—7 of Fig. 6;

Fig. 8 is a plan view of an assemblage of rectangular shingles having transverse ramps; and

Fig. 9 is a section on the line 9—9 of Fig. 8.

Referring to Fig. 1 of the drawing, the shingle *e* has a rectangular portion *e'* and a triangular portion *e''*, offset from one another by a relatively abrupt ramp *3^e*, and the triangular portion has a relatively abrupt ramp *4^e* spaced substantially the same distance from the ramp *3^e* as the distance be-

tween the latter ramp and the lower edge of the rectangular portion. An assemblage of these shingles is shown in Figs. 2 and 3, from which it will be seen that the ends *x* of the shingles in a row 2 are in alinement with the upper edges of the ramps *3^e* in a row 1, and similarly, the ends of the rectangular portions of the shingles in successive rows 3, 4 and 5 aline with the upper edges of the ramps *3^e* of the shingles in the immediately lower rows. This arrangement, as best shown in Fig. 3, gives the effect of a double thickness along the lines of the ramps *3^e*, as the edges *x* terminate in line with these ramps. This is desirable from an architectural point of view.

The shingle *f* shown in Figs. 4 and 5 is the same as that shown in Fig. 1, except that the lower corners of the triangular portion *f''* are cut off, as indicated at *5^f*, and the ends *6^f* of the rectangular portion *f'*, below the ramp *3^f*, are cut off, making the rectangular portion slightly shorter than said ramp. The triangular portion has a ramp *4^f* at the same distance from the ramp *3^f* as is the lower edge of the rectangular portion from the lower ramp.

In Fig. 6 is shown a part of a roof covering composed of shingles *f*. The shingles in the lowermost row are indicated at 6; in the next higher row at 7, and 8 indicates a shingle in a third row. In assembling the shingles in rows, the cut-off ends *5^f* of the triangular portions abut against one another, and as the rectangular portions below the ramps *3^f* are shorter than the ramps, spaces 9 are left between the adjacent shingles of the row which has an architectural advantage over the covering shown in Fig. 2, wherein the rectangular portions of the shingles abut against one another and form an unbroken row. When the next row of shingles 7 is laid, the ramps *3^f* of the shingles in this row abut against the ramps *4^f* in the row 6 and the lower edges of the shingles in the row 7 are in alinement with the upper edges of the ramps *3^f* in the lower row, giving the effect of double thickness at the lower ends of the shingles. The cut-off ends of the triangular portions abut against one another in the row 7, and because of the shortening of the rectangular portions, a space *9^a* is left between the rectangular portions of adjacent shingles. Similarly, when shingles 8 are arranged in a third row, the rec-

tangular portions of the shingles will be spaced apart.

It is to be noted that as the ramps 3^t of one row abut against the ramps 4^t of another row, and as the edges 5^t of the shingles in each row meet, any rain driven into the open spaces $9-9^a$ will be prevented from passing upwardly under the shingles by the ramps 4^t in one row and by the ramps 3^t in the overlying row, the ends of which meet and lie against the ramps 4^t of the lower row.

In Figs. 8 and 9, I have shown shingles g which are rectangular in form and with ramps 1^s , 2^s , running parallel with the upper and lower edges of the shingles, these edges being spaced from the ramps a distance equal to that between the ramps so that when the shingles are laid in rows, the lower edges y of the shingles of one row will be in alignment with the upper edges of the ramps 2^s of the shingles of the next lower row, and the ramps 2^s of the upper row will lie against the ramps 1^s of the next lower row. Thus, the effect of double thickness will be pro-

duced along the lower edges of the shingles in the rows.

What I claim is:

1. A roof covering comprising shingles arranged in overlapping rows, each shingle comprising a plurality of plane parts offset from one another by relatively abrupt transverse ramps, the ends of the shingles in one row registering substantially with the upper edges of ramps in the shingles of another row.

2. A roof covering comprising shingles arranged in overlapping rows, each shingle having three plane parts offset from one another by upper and lower transverse ramps, the lower ramp in a shingle of an upper row lying against the upper ramps in shingles of a lower row, and the lower ends of the shingles in the upper row registering substantially with the upper edges of the lower ramps in the shingles of the lower row.

In testimony whereof I hereunto affix my signature.

THOMAS DENTON MILLER.
